UNITED STATES PATENT OFFICE

THEODORE BOSSARD, OF SALT LAKE CITY, UTAH, ASSIGNOR TO RESEARCH ENGINEERING LABORATORIES, INC., A CORPORATION OF UTAH

FUELING SYSTEM

Application filed August 14, 1929. Serial No. 385,714.

My invention relates to automobiles and more particularly to fueling systems for drawing the fuel to the motor and has for its object to provide a new and efficient fueling system which will draw the fuel to the motor without the use of vacuum tank, pump, or other devices used in the present day systems.

A further object is to provide a new fueling system for motors which will draw the fuel to the motor from the tank by a system of boosters which boosters increase the suction of the intake manifold of the engine to such an extent as to draw the fuel and fuel vapors from the tank directly to the intake manifold in a substantially complete carbureted condition.

A further object is to provide a fueling system which when installed in an automobile will provide a system which will have few moving parts, few operations for the driver, and which will completely carburet the fuel before it is introduced into the motor thereby giving greater mileage, more smooth running of the motor and quicker and even acceleration of the motor.

These objects I accomplish with the device illustrated in the accompanying drawings in which similar numerals and letters of reference indicate like parts throughout the several views and as described in the specification forming a part of this application and pointed out in the appended claims.

In the drawings in which I have shown the best and most preferred manner of building my invention Figure 1 is a longitudinal vertical section of the device with parts cut away. Figure 2 is a side elevation of the air regulating valve. Figure 3 is a section of the upper air and fuel mixing portion of the Venturi nozzle or jet. Figure 4 is a section of the lower air inlet end of said jet. Figure 5 is a plan view of the booster casting used in the fuel supply tank.

In the drawings I have shown the fuel supply tank as A, and the carburetion portion of my device as B. The carburetion portion B is provided with a flange 1 on the top side thereof whereby the device is secured to the intake manifold of an engine. The portion

B is made of a cylindrical body 2, having the lower end constricted at 3 to form a valve seat 4. The lower end of the casting which forms the body has a cylindrical air inlet 5 formed thereon with the bore of the inlet 5 at right angles to the bore of the body B. The lower end 6 of the casting is closed and on one side thereof I provide an injector casting 7. Within the constricted portion 3 of the body B I form a concentric casting 8 which casting is secured to the body B on the side adjacent the injector casting and the bottom end of the body B is bored and threaded at 9 to receive a closure plug 10. Through the opening 9 I then bore out the center of the casting 8 into different sized bores, the lower bore 11 being larger, the next 12 being slightly smaller and the small bore 13 being carried out through the top of the casting. Into the bore 12 I press a fuel and air control jet 15 which jet is formed with a frusto-conical boss 16 on the lower end thereof and with the bore 17 thereof tapered from the conical end 16 to the top end 18. This jet is more clearly shown in Figure 3 of the drawings and the upper portion 19 of the jet is made of smaller diameter than the lower portion 20. The portion 20 is that portion which is pressed into the end of the bore 12 and the upper portion 19 extends up through to the top end of the casting 8. In the bore 11, I then press an air jet 21 which air jet 21 has the lower end of the bore thereof curved outwardly at 21a to the outer periphery of the jet. The bore 22 of the said jet is of smaller diameter than the small end of the tapered bore of the jet 15. The top end 23 of the said jet 21 is formed frusto-conical and extends up into the casting 8 to near the lower end of the frusto-conical boss 16 leaving a space 24 therebetween. When the two jets 15 and 21 are inserted in the casting 8 the form of the two frusto-conical ends 16 and 21 leave an annular triangular shaped groove 25 therebetween with the peak of the triangular shaped space merging into the space 24. I then bore the bottom end of the injector or accelerator well casting 7 and extend the bore 25a therein to near the top end thereof and diagonally 100

from the bottom of the said bore I bore ports 26 and 27 with the port 26 connecting the bore 25a with the annular groove 25 in the bore 12 of the casting 8, and the port 27 is connected with an inlet bore 28 in a boss 29 formed on the side of the casing 7. A closure plug 30 is screwed into the bottom end of the bore 25a to retain all fuel therein. Through the top end of the casing 7 I bore a small hole 31 and within the bore 25a I 10 provide a spring 32 and an injector plate piston 33 and which plate 33 has a guide shaft 34 on the top side thereof. The said shaft 34 extends up through the hole 31 into the open air thereabove. Within the bore 13 of the casting 8 and between the inner walls thereof and the outer walls of the upper portion 18 of the jet 15 I provide a sliding cylindrical valve member 35. The said valve 35 is formed with a head 36 on the top end 15 thereof adapted to close the valve seat 4 in the body B, and the lower cylindrical stem 36a of the valve is carried in the annular space between the walls of the bore 13 and the outer walls of the jet 15. This provides 20 a slow moving jet valve for the air cushion formed in the space 37 thereunder and will act both to retard the upward motion and also the downward motion of the valve to a slight degree. A choke valve 37a is pivoted within the air inlet 5 to control the flow of air therethrough for starting the motor. In the top end of the body B I provide a throttle valve 38 pivoted on a shaft 39 and having one outer edge 40 thereof adapted to close 25 a port 41 in the side wall of the casting. The said port 41 is bored through a boss 42 formed on the side of the body B and a control needle valve 43 is screwed into the outer end of the bore to control the flow of fuel therethrough. 30 A vertical bore 44 is also through the boss 42 and a pipe 45 is connected to the lower open end thereof, which pipe is to carry the necessary fuel for idling the motor and which pipe is carried back and down into the fuel supply tank. The top end of the bore 44 is closed by a control plug 46 and an air port 47 is bored at an angle through the top end of the boss joining the bore 44 above the level of the bore of the port 41, and the plug 46 is adapted to partially or entirely close the port 47 by screwing the plug 46 down into the bore 44 sufficient distance. This is the 35 means of providing an air control for the air port 47.

To the bore of the boss 29 I connect a pipe 48 which pipe 48 leads back to an elbow 49 and another pipe 50 extends down through an inlet opening into the fuel supply tank A. Through the top side of the tank A I provide a cylindrical socket 51 and to the socket 51 I connect an elbow 51a on an air pipe 52, this air pipe 52 leads to near the carburetion portion of my device and a pipe 53 is placed therearound with the other end of the pipe 53 40 surrounding the joining nut of the pipe 48.

and the boss 29. Another pipe 54 leads from the pipe 53 to a source of warm air preferably to a heater surrounding the exhaust pipe of the engine with which the device is being used. An upright pipe 55 is then placed with- 70 in the bore of the socket 51 and said pipe leads down into the tank A, and is connected with a cylindrical screen carrying casting 56. The lower end of the casting 56 is secured through the bottom of the tank in a threaded hole 57 and the bottom end 58 of the casting 56 is closed by a plug 59. The said casting 56 is provided with two spaced apart screen carrying flanges 60 and a screen 60a is secured therearound. A port 61 connects the bore of the casting with the screened area surrounding the medial portion of the casting. To the bottom end of the pipe 50 I secure a booster member 62 and the end of the idling pipe 45 is within and carried through the pipe 50 to the point just depending into the bore of the booster 62. The said booster is made of a casting having a tapered bore 64 through the top end thereof. The extreme end of the tapered hole or bore is with- 75 in a frusto-conical boss 67 on the inner face of the bore 66 in the lower end thereof. A cylindrical plug 68 is pressed into the bore 66 and the lower edges of the bore thereof are tapered outwardly to form a tapered hole 69. The space left between the end of the plug 68 and the end of the boss 67 forms an annular groove 70 therebetween and a port 71 connects the groove 70 with the port 61 thereby 80 providing means of allowing fuel to enter the groove from the tank. The lower end of the casting 63 is formed with three spacer lugs 73, 74 and 75 with the bore or port 71 passing through the lug 75 to connect it with the port 61 and with the other lugs to space the booster casting from the side walls of the casting 56, so that air from the pipe 55 and the pipes 53 and 52, may pass there- 85 through and up through the booster through the bore of the plug 68.

100 The operation of my device is as follows:

When the motor is rotated suction is created and the throttle is opened to start the motor the suction of the motor drawing up through the carburetion portion B is increased by the passage of air through the jets and the force thus augmented draws the air from the chamber in the casing 7 and through the pipe 48 and the pipe 50 from the booster 62: air is drawn through the pipes 54, 53, 52 and 55 and through the plug 68 in the booster 62. The suction is again augmented by the booster and fuel is drawn through the ports 71 and 61 up through the booster where it is mixed with some air and drawn in a gaseous stage through the pipes 50 and 48 into the injector chamber and thence through the port 26 into the annular groove 25 and thence up through the jet 15 into and through the body B to the engine. When starting the motor 110 105 115 120 125 130

after it has once been run there will be sufficient fuel in the injector chamber to give a free flow of fuel for instant starting and as the motor accelerates, the plate 33 is drawn 5 suddenly down forcing all the fuel and vapor in the casing into the jet whence it is carried to the engine. If the driver wishes to suddenly accelerate his motor the injector acts similarly giving a supply of instantaneous 10 combustible fuel for quick pick up. As the motor is accelerated the suction of the motor draws the compensating valve 35 upwardly allowing air to pass in unmixed quantity through the air inlet 5 and the weight of the 15 valve will compensate allowing only the correct amount of air to pass therethrough.

The idling of the motor is controlled by the throttle valve 38 having the edge thereof open or close the port 41 depending on the amount 20 of fuel needed for idling and the air needed for idling passes through the port 47 into the port 41. The needle valve 43 may be used to give the correct mixture of fuel through the port 41 and the fuel for idling is 25 drawn through the pipe 45 from the top end of the booster 62 in the tank A. It will be obvious that the motor can be shut off completely by closing the throttle valve sufficient to entirely close the port 41 by the edge of 30 said valve.

Having thus described my invention I desire to secure by Letters Patent and claim:

1. In a fuel system for automobiles the combination of a cylindrical body portion 35 having a valve seat formed therein; an air cushioned valve carried therein and adapted to close said seat; a concentric casting within said casing; a jet carried in said casting; having the bore thereof tapered from the top to 40 the bottom; another jet spaced therefrom within said casting forming an annular chamber therebetween, said chamber being in open connection with the fuel supply line; a spring controlled injector in said supply line adapted 45 to be actuated by sudden increased suction from the motor when accelerated; means to introduce idling fuel into said casing adjacent the throttle valve; a throttle valve to control the entire system; and a booster im- 50 mersed in fuel in the fuel supply tank to vaporize the fuel and increase the suction through the lead line connected therewith.

2. In a fueling system for automobiles the combination of a cylindrical casing having 55 a valve seat formed therein and a perforated compensating air cushioned valve adapted to close or open the seat commensurate with the suction passing therethrough; a Venturi type of fuel jet carried medially in said casing within said valve; a booster of the Venturi type carried in the fuel supply tank; a lead line connecting said booster with said fuel jet; an idling pipe carried within said lead line said idling pipe leading into said casing 60 at the point of throttle control; and means

within said tank to allow fuel to flow into said booster to draw air into the bottom end thereof increasing the force of suction drawing fuel into the lead line and into the jet.

In testimony whereof I have affixed my signature.

THEODORE BOSSARD.
